Primary Examiner — Catherine A Tuttle(74) *Attorney, Agent, or Firm* — Steven Ivy P.C.(57) **CLAIM**

I claim the ornamental design for a self standing golf tee, as shown and described.

DESCRIPTION

FIG. 1 is a front, top, and right side perspective view of a self standing golf tee showing my new design;
FIG. 2 is a right elevation view thereof;
FIG. 3 is a left elevation view thereof;
FIG. 4 is a front elevation view thereof;
FIG. 5 is a rear elevation view thereof;
FIG. 6 is a top plan view thereof; and,
FIG. 7 is a bottom plan view thereof.
